TIMER CONSTRUCTION

George S. Clemens, Evanston, Ill.

Application August 6, 1948, Serial No. 42,862

8 Claims. (Cl. 161—1)

1

My invention relates to timers and like devices wherein an electrical circuit condition is established for a predetermined time interval or while a predetermined event takes place.

It is frequently desirable to provide mechanisms wherein an operation may be manually initiated and will continue for a predetermined time thereafter. Thus, in hand drying machines used in public washrooms, it is desirable to provide a single push button operable to initiate operation of the air heating elements and the blower. However, it is also necessary that the heating elements and the blower be deenergized after a predetermined period of time to avoid the chance of continuous operation of the mechanism when it is not in fact being used.

Heretofore, the timer mechanisms for blowers and like devices have included circular cams driven by timer motors and which have a peripheral notch in which the cam follower falls to deenergize the unit. While this limits the time of operation of the unit, it is frequently necessary to hold the manual start button for a considerable time period before the mechanism positively starts. More frequently, users unacquainted with the device will repeatedly press the starting button, thereby causing the motor to execute a number of partial starts in succession. This latter operation is highly undesirable for it causes the motor to operate for long periods under substantially locked motor conditions with the consequent motor overheating and blowing of fuses.

It is therefore a general object of the present invention to provide an improved mechanism for use in timing devices.

A further object of the present invention is to provide an improved timer mechanism which is positively started by a single operation.

Another object of the present invention is to provide an improved timer adapted for operation with timer motors of various speeds.

The novel features which I believe to be characteristic of my invention are set forth with particularity in the appended claims. My invention itself, however, may best be understood by reference to the following description taken in connection with the accompanying drawings in which:

Figure 1 is a diagrammatic view of a timer embodying the present invention as applied to a hand drier;

Figure 2 is a fragmentary portion of Figure 1 showing the timer in the beginning of an operating cycle;

Figure 3 is a cross-sectional view through axis ⁵⁵ III—III, Figure 2; and

Figure 4 is a fragmentary cross-sectional view through axis IV—IV, Figure 2.

As shown in Figure 1, the timer of the present invention includes a timer motor 10 which operates to rotate shaft 12 in the clockwise direction when energized at terminals 10a and 10b. The shaft 12 receives the cam 14 and the holding member 16 which operate as described in detail hereafter.

10 The cam follower indicated generally at 18 rides on the cam 14. This follower includes a button 20 positioned to ride on cam 14 and a manual start button 22 positioned to swing button 20 free of cam 14 when depressed as indicated by arrow 22a, Figure 2. The cam follower also includes a pair of contact elements 24 and 26 which serve to establish an electrical circuit when button 20 is in the raised position of Figure 2.

20 The contacts 24 and 26 serve to establish an electric circuit to the drier motor M, the heater element H, and to the timer motor 10. These circuits may be traced from the terminal 28 to the common connection of motor M, heater H and timer 10, through these elements, to the upper conducting leaf 26a which extends to contact button 26. From button 26, the circuit may be traced to button 24 and through conducting leaf 24a back to terminal 30.

30 The cam follower assembly 18 may be any one of several types well known in the art. In the specific type shown, the button 20 is mounted on a lengthy flexible leaf spring 32 which is anchored to base 34 as shown. A flexed spring 36 extends from spring 32 to the upper arm 26a which sustains contact 26. The ends of the spring 36 are attached to spring 32 and arm 26a by the protuberances 26b and 32a, Figure 4, which are received in mating holes in the end portions of spring 36.

40 When button 20 rides in notch 14a or 14b of cam 14, spring 32 tends to straighten, thus shifting the outer end of the spring 36 in the downward direction below the tip of the arm 26a. The spring 36 thereupon exerts an upward component of force on arm 26a and lifts that arm to a spaced position relative to button 24 as shown in Figure 1.

When spring 32 is flexed upwardly as shown in Figure 2, the outer end of spring 36 swings to a position above the tip of arm 26a. This causes spring 36 to exert a downward component of force on arm 26a and thereby flexes arm 26a to the contact making position of Figure 2.

45 Arm 32 serves to back up arm 26a to limit the forces exerted thereon.

The cam 14 is held on shaft 12 by the hub 40, Figure 3, which is retained on that shaft by the set screw 40a. The hub 40 snugly receives the cam 14 to cause rotations of the latter in accord with the rotations of the shaft. The hub 40 further has a reduced portion defining an annular wall. The holding member 16 is loosely received on this reduced portion and is thus held against the face of the cam 14.

Spaced pins 42 and 42a extend in the axial direction from cam 14 to define limits of motion of the holding member 16. The pin 44 extends axially from the holding member 16 in like fashion to receive spiral spring 46 which is anchored at its opposite ends to pin 42. Spring 46 acts to urge holding member 16 in the clockwise direction relative to cam 14, thereby urging it to the registered position relative to notches 14a and 14b as shown in Figure 2.

The holding member 16 acts to hold arm 32 in the position of Figure 2 when button 22 is depressed. This results from the action of spring 46 which snaps member 16 to that position when member 20 is swung free of the periphery of the cam 14.

The member 16 extends a slight distance beyond the periphery of the cam 14 and thus engages the member 20 as the cam rotates. Consequently when the motor 10 is once set in motion, it continues to rotate cam 14 until one half revolution is executed, at which time the member 20 will engage the forward edge of member 16. Further rotation of the cam 14 causes holding member 16 to swing in the counter-clockwise direction relative to cam 14, thereby uncovering notch 14a or 14b as shown in Figure 1 and permitting contacts 24 and 26 to open, thus stopping motor 10.

From the foregoing description it will be apparent that I have provided a unit capable of actuating heater H and blower motor M for a pre-selected time determined by the speed of rotation of motor 10 and the angular distance between notches 14a and 14b. Moreover, this operation is achieved by a single actuation of the button 22 and there is no tendency for the unit to stop after actuation due to failure of cam follower 20 to ride out of notch 14a or 14b during the time button 22 is actuated.

Moreover, it will be apparent that the time period may be preselected relative to the motor speed by appropriate choice of notches 14a and 14b. Commercial timer motors are standardized at a speed of one revolution per minute so that by use of the two notch cam shown these motors can be utilized to establish a 30 second running time of the unit. This correspondingly reduces the expense of the structure.

While I have shown and described a particular embodiment of my invention, it will, of course, be understood that I intend by the appended claims to cover all variations and modifications coming within the true spirit and scope thereof.

What I claim as new and desire to secure by Letters Patent of the United States is:

1. In a timer switch of the type wherein a cam having a notch is rotated at predetermined speed when an electric circuit condition is established and a cam follower rides on said cam to establish said condition when it rides out of said notch, the improvement which comprises a holding member movably mounted relative to said cam and in one position adapted to overlay substantially the entire extent of said notch to de-

fine a cam surface to hold said follower free from said notch, and means operable to urge said member to said one position to establish positively said circuit condition when said follower is swung free of said cam, said holding member having portions for engagement with said follower to move said member out of said one position as said cam rotates.

2. In a timer switch of the type wherein a circular cam having a peripheral notch is rotated at predetermined speed when an electric circuit condition is established and a cam follower rides on said cam to establish said condition when it rides out of said notch, the improvement which comprises a holding member mounted against the face of said cam for swinging movements about the axis of the cam and operable in one position to overlay substantially the entire extent of the notch to hold said follower free from said notch, and spring means operable to urge said member to said one position to establish positively said circuit condition when said follower is swung free of said cam, said member having a portion extending radially beyond said cam to be engaged by said follower to swing said member out of said one position as said cam rotates.

3. A positively setting cam mechanism for a device of the type wherein an operation progresses when a cam follower assumes one position and stops when the follower has a second position, said mechanism comprising means defining a cam surface to receive said follower and operable to hold said follower in said first position and having a notch to receive said follower to permit said follower to move to said second position, a holding member movably affixed to said means and operable in one position to define a cam surface overlaying substantially the entire extent of the notch to hold said follower out of said notch, and means biasing said holding member to said one position, said holding member having portions to engage said follower to move said member out of said one position as said cam rotates.

4. A cam for a timer switch comprising a disk having a peripheral surface with an inwardly extending notch to receive a cam follower, a holding member mounted for rotations relative to said disk and about the axis of the disk, said member being adapted to register with said notch when in one position to define a cam surface overlaying substantially the entire extent of the notch to hold said cam free of said notch, spring means operable to urge said member to said one position and stop means operable to hold said member in said one position against the action of said spring means, said holding member defining a wall extending from said peripheral surface to engage said follower and swing said member out of registry with said notch.

5. A timer mechanism comprising in combination, a cam having a peripheral surface with a notch, a cam follower adapted to ride on said surface and to establish a first circuit condition when on said surface and a second circuit condition when in said notch, means operable to rotate said cam when said first circuit condition is established, a holding member mounted for movements about the axis of the cam to registry with said notch to define a cam surface overlaying substantially the entire extent of the notch for holding said follower out of said notch, spring means operable to bias said member to said registered position, and stop means operable

to hold said member in said registered position against the bias of said spring means, said member defining a catch element to engage said follower and swing said member out of registry with said notch as said cam rotates.

6. A timer mechanism comprising in combination, a cam having a peripheral surface with a notch, a cam follower adapted to ride on said surface and to establish a first circuit condition when on said surface and a second circuit condition when in said notch, means operable to rotate said cam when said first circuit condition is established, a holding member mounted for movements about the axis of the cam to registry with said notch to define a cam surface overlaying substantially the entire extent of the notch to hold said follower out of said notch, and spring means operable to bias said member to said registered position, said member defining a catch element to engage said follower and swing said member out of registry with said notch as said cam rotates.

7. A cam for use with a follower, said cam comprising in combination a disk having a pair of diametrically opposed peripheral notches, a holding member mounted adjacent the face of said disk for movements about the axis of the disk, said member having diametrically opposed portions for registry with said notches to define cam surfaces overlaying substantially the entire extent of the notches for holding said follower out of said notches, spring means operable to urge said member to registry with said notches, and stop means operable to hold said member in registry against the action of said spring means, said member having portions extending beyond said disk for engagement with said fol-

lower to swing said member out of registry when said disk is rotating.

8. A cam for use with a follower, said cam comprising in combination, a disk defining a cam surface having a pair of diametrically opposed notches, a hub for said disk defining a wall in spaced relation with the face thereof, a holding member interposed between said wall and said face and loosely fitted on said hub, said member defining a pair of diametrically opposed cam portions operable to overlay substantially the entire extent of the notches to hold said follower out of said notches when said member is in registry therewith, a pair of axially extending stop elements mounted on said disk and defining a limited range of movement of said follower, one extreme of said range being in registry with said notches, and spring means operable to urge said member towards said extreme of movement, said member extending beyond the periphery of said disk to define a wall for engagement with said follower to swing said member out of registry with said notches as said cam rotates.
